UNITED STATES PATENT OFFICE.

JONATHAN E. WHEELER, OF WESTPORT, CONNECTICUT.

DESIGN FOR BUTTONS FOR WEARING-APPAREL.

Specification forming part of Design No. **6,947**, dated October 7, 1873; application filed July 30, 1873.
[Term of Patent 14 years.]

To all whom it may concern:

Be it known that I, JONATHAN E. WHEELER, of Westport, in the county of Fairfield and State of Connecticut, have invented a new and original Design for Button for Wearing-Apparel; and I do hereby declare the following, when taken in connection with the accompanying drawings and the letters of reference marked thereon, to be a full, clear, and exact description of the same, and which said drawings constitute part of this specification, and represent the button enlarged to four times full size.

This design relates to the ornamentation of metal buttons, such as used for gentlemen's wearing-apparel, and known to the trade as suspender-buttons; and consists in the pecu-

liar ornamentation of the surface of the button, as shown in the accompanying illustration, and more fully hereinafter described.

The outline of the button is round. In the center a cavity is formed and pierced, in the usual manner, and the surface between the cavity and edge is ornamented by numerous radial flutes, as shown, and with or without a beaded edge.

I claim—

The design for button, as shown in the accompanying illustration, and herein described.

JONATHAN E. WHEELER.
